[57] CLAIM

The ornamental design for a tooth for dredge cutter head or the like, substantially as shown.

DESCRIPTION

FIG. 1 is a front elevational view of the tooth for dredge cutter head or the like showing my new design;
FIG. 2 is a left side elevational view thereof;
FIG. 3 is a right side elevational view thereof;
FIG. 4 is a rear elevational view thereof, with a portion broken away to illustrate the cavity therein;
FIG. 5 is a top plan view thereof;
FIG. 6 is a bottom plan view thereof; and
FIG. 7 is a cross-sectional view thereof taken along line 7—7 of FIG. 1.
